UNITED STATES PATENT OFFICE.

WILLIAM M. AMMERMAN AND EDWIN J. TOOF, OF NEW HAVEN, CONNECTICUT, ASSIGNORS TO SAID TOOF.

SEWING-MACHINE.

SPECIFICATION forming part of Letters Patent No. 587,908, dated August 10, 1897.

Application filed October 24, 1890. Serial No. 369,245. (No model.)

To all whom it may concern:

Be it known that we, WILLIAM M. AMMERMAN and EDWIN J. TOOF, citizens of the United States, and residents of New Haven, county of New Haven, and State of Connecticut, have invented new and useful Improvements in Sewing-Machines, of which the following, taken in connection with the accompanying drawings, is a specification.

This invention relates particularly to the feeding mechanism of sewing-machines; and it consists in the construction and combination of parts for operating and regulating the movements of the feed device proper, as hereinafter set forth in detail, and pointed out in the claims.

Referring to the drawings, Figure 1 represents the bottom of the bed-plate of a sewing-machine provided with our improved feeding and feed-adjusting mechanism. Fig. 2 is an end view of the same through line $x-x$; Fig. 3, a top view of the feed-adjusting-lever-regulating device; and Fig. 4, a detail view of the feed-adjusting lever from the side opposite that shown in Fig. 1, showing its mode of pivotal connection with its supporting-plate.

In the drawings, A represents the bed-plate of a sewing-machine; B, the feed-bar, by which the serrated dog b, which projects above the surface of the cloth-plate to engage with and feed the material being stitched or otherwise operated upon, is carried and operated. The said feed-bar is carried by and receives its vertical motion from two rocking disks or plates C C, which are pivotally supported between lugs or projections a a on the bed-plate A. The feed-bar is connected with said disks by means of pins or projections c, located on the latter, which project into horizontally-arranged slots b' in the said feed-bar. Said disks are connected by a rod C', pivotally connected at each end thereto, as more clearly shown in Fig. 2, and said connecting-rod is engaged and operated by a vibrating lever D, which serves to vibrate said connecting-rod and give the disks C C, connected thereto, a rocking motion, which action causes the pins

or projections c thereon to rise and fall, as will be readily understood, and give the feed-bar carried thereby its vertical or up-and-down movement.

The vibrating lever D is centrally pivoted on a stud A', located on the bed-plate A, and at one end embraces and is operated by a cam or eccentric located on a vertically-arranged rotating shaft E, which receives its motion from the upper driving-shaft.

The feed-bar receives its longitudinal movement through the medium of a vibrating lever F, which is centrally slotted to slide and fulcrum on the said stud A' and at one end connects or engages with said feed-bar to operate the latter and at its opposite end is provided with a pin or projection thereon which extends and operates within a groove or guideway h, located in one end of a feed-adjusting lever II, in a manner and for the purpose as will hereinafter be described.

F represents a connecting-rod pivotally attached at one end to the said lever F and at its opposite end embraces a cam or eccentric also located on the said vertically-operating shaft E, by which it is operated to reciprocate said lever F and cause it to vibrate (and thereby the feed-bar) by reason of the pin or projection at one end thereof operating in the said guideway h, which is adapted to be adjusted to a greater or less angle in its relation to the length of the lever F, according to the length of the throw of the feed desired, as it will be readily understood that the degree at which the angle of said guideway is set, whether greater or less, will regulate the length of vibrations of said lever accordingly. The feed-adjusting lever II, which is adapted to be adjusted from the upper surface of the cloth-plate by a connecting setscrew h', is provided with two pivot-pins h² h², arranged thereon in a line parallel with the groove or guideway h therein, which extend into slots h³ h³, located in a plate h⁶ secured to the under side of the bed-plate, as shown. These slots h³ h³, in one end of which the pivot-pins h² have their bearing, are ar-

ranged in a line at right angles to the feed-lever F, and when the lever II rests on both its pivot points or centers and the guideway h therein is in a line parallel with the length 5 of the lever F, or when the end of the lever F is immediately over one of said pivotal centers of the lever II, the feed-bar engaged by the opposite end of the lever F is in its normal starting position at the front of its 10 raceway in the cloth-plate of the machine. By moving or adjusting said lever II from one to the other of its pivotal centers reverses the angle of the guideway h therein and changes or reverses the throw or feed of 15 the feeding device accordingly, as will be readily understood.

The object of the lever II operating on two pivotal centers, as described, is to throw the whole length of the guideway h to one or the 20 same side of the line of its pivotal centers when adjusted on either of the same, in order that the lever F, engaged and guided thereby, may cause the feed-dog to start when feeding forward and end when feeding backward at a normal position at the front end of 25 its raceway.

The feed-adjusting lever II is provided with a pin or projection h⁴ thereon, which projects and operates in a groove h⁵, located 30 in the plate h⁶ and formed in the arc of the circle of each pivot-point of said lever, the object of said groove, as described, being to prevent an undue vertical movement of the pivot-pins h² h³ and insure their proper operation. 35

In order to regulate the adjustment of said lever II when moved to change the direction of the feed in such manner that the length of throw of the feed may be the same when 40 adjusted to feed in opposite directions alternately, we provide two arms or levers I I, adapted to be secured to the upper surface of the cloth-plate or a plate secured thereon, and which at said pivoted end are of an enlarged circular shape and provided with teeth 45 on their adjacent edges, adapted to mesh into each other in order that their opposite free ends, which project across the path of the adjusting-screw h', may be moved or operated 50 in unison to change the length of the slot a', which forms the path in which the adjusting-screw h' is adapted to be moved. Said regulating arms or levers are secured or held stationary when adjusted to the desired position by means of a clamping-plate i, secured above the pivoted end of said lever, and by a set-screw i', which latter is adapted 55 to clamp said plate. One of said arms I I is provided with a slot i² for the passage of the set-screw i' and allow said arm or lever to be moved or adjusted.

We claim—

1. In a sewing-machine, the combination with the feeding device and its operating-le-

ver, of a stitch-regulating mechanism, comprising an adjusting-lever having a groove therein to receive and guide a pin located on said feed-operating lever, and provided with two pins or projections arranged in a line parallel with the said groove therein, a stationary plate having two guideways in which the pins on said lever extend to pivotally support the latter, means for holding said lever with the groove therein in a stationary adjusted position, and means for giving vertical movement to the feed, substantially as described and for the purpose set forth. 65

2. In a sewing-machine, the combination with the feeding device and its operating-lever, of a stitch-controlling lever having a guideway therein to receive a pin or projection on said operating-lever, and a pair of pivoted disk-levers operatively connected whereby the arm with which each is provided may be moved simultaneously to and 80 from a given point, whereby the throw of the stitch-controlling lever is restricted at the will of the operator, and means for giving vertical movement to the feed device, substantially as set forth. 85

3. In a sewing-machine, the combination with the feed-bar, and means for giving the same its vertical movement, of a centrally-pivoted vibrating lever engaging at one end with said feed-bar, a pivoted adjusting-lever provided with a groove therein to receive and guide a pin or projection on said vibrating lever, means for holding said grooved adjusting-lever in a stationary adjusted position, and a pair of pivoted adjustable stops arranged to move simultaneously for regulating the movement of said adjusting-lever, substantially as set forth. 90

4. The combination in a sewing-machine, with the driving-shaft, feed-bar, two crank-disks supporting said bar and united by a connecting-rod, and means operating said crank-disks to give a vertical movement to the connected feed-bar, of a centrally-pivoted vibrating lever connecting at one end with 100 said feed-bar, and at or near its opposite end provided with a pin or projection thereon, a pivoted lever provided with a groove arranged to receive said pin or projection, means for holding said grooved lever in a stationary adjusted position, and a driving-rod connecting with said vibrating lever and operated by a cam or eccentric located on the driving-shaft, substantially as and for the purpose set forth. 105

5. In a sewing-machine, the combination 110 with the driving-shaft, and feed-bar, of two crank-disks supporting said feed-bar and united by a pivotally-connected rod, two centrally-pivoted driving-levers connecting with said feed-bar and connecting-rod respectively, and means for operating said levers from the driving-shaft, substantially as described and for the purpose set forth. 115

6. In a sewing-machine, the combination with the feed-bar, means for giving rise and fall to the same, and a vibrating lever connecting at one end with said feed-bar, of a feed-adjusting lever having two pins or projections extending within guideways in the bed-plate to move and pivot therein, and provided with a transverse groove or guideway to receive a pin or projection on said vibrating lever, and with a guiding-pin which ex-

tends and operates within a groove in the bed-plate, and means for adjusting said feed-adjusting lever, substantially as and for the purpose set forth.
